UNITED STATES PATENT OFFICE

CHARLES W. VALENTINE, OF WATERTOWN, NEW YORK, ASSIGNOR TO THE BAGLEY AND SEWALL COMPANY, OF WATERTOWN, NEW YORK, A CORPORATION OF NEW YORK.

APRON BOARD FOR PAPER-MAKING MACHINES.

Application filed January 22, 1926. Serial No. 82,900.

This invention relates to certain improvements in Fourdrinier paper making machines and has particular reference to an improved apron board for the web forming end of these machines.

In these Fourdrinier machines, as ordinarily constructed, the stock or pulp from which the web is formed is delivered to the making wire through an opening between what is known as a slice and a cooperating member generally termed an apron or apron board. In these machines employing an apron board it is desirable that the board should be parallel across the machine with the wire and breast roll over which the wire passes, and it is also desirable that the gap between the board and the wire be as small as possible without danger of the board rubbing the wire. It is further desirable that the board may be adjusted so that these conditions may be obtained with ease and sureness by the operator.

It is a special object of the invention to provide an improved apron board of such flexibility or looseness that it may be practically self aligning with the breast roll or wire.

A further object of the invention is to produce an improved apron board which, after the alignment of the breast roll or wire, may be adjusted so that a uniform gap between the board and the roll or wire may be obtained widthwise of the machine.

With these and other objects not specifically referred to in view, the invention consists in certain novel parts, arrangements and combinations which will be described in connection with the accompanying drawings and the novel features pointed out in the claims hereunto annexed.

In these drawings,—

Figure 1 is a sectional side view of so much of the making end of a Fourdrinier machine as is necessary for an understanding of the invention, and

Figure 2 is a sectional front view, partly broken away, the section being taken on line 2-2 of Fig. 1.

Referring now to these drawings, the breast roll is marked 1 and the making wire 2. Pulp or stock is delivered to the wire from a head box indicated at 3 under a slice indicated at 4.

Cooperating with this slice is an apron board of improved construction, this apron

board being so constructed and arranged that it may be positioned so that its edge is parallel with the breast roll, thus compensating for any deflections in the board or irregularities in the roll, and adjusting means are provided whereby a uniform gap between the edge of the lip of the board and the roll may be obtained.

The specific means employed for this purpose may be varied. The construction shown, however, is a preferred one and will be described as illustrative of the invention. As shown, the apron board comprises a rigid portion 5 which includes a frame 6, this framing in turn being supported by suitable standards 7. The front of the rigid part 5 has a flexible or loose extension in the form of separate plates 8, these plates being secured to the rigid part of the board by means of a thin flexible sheet of metal 9. The front edge of this sheet extends somewhat beyond the plates 8, as indicated at 10, and lies closely adjacent the wire, the part being positioned so that the gap between the edge or lip 10 and the wire is as small as possible.

The plates 8 are supported by arms 11 preferably integral therewith and these arms are supported so that they can have a rocking movement. As shown, the arms are supported on an extension 12 from the frame 6, before referred to, and the ends of the arms are rounded, as indicated at 13, so that they are free to rock on the extension 12. The arms are locked against movement by suitable locking devices shown in the form of screws 14 having operating handles 15. These screws pass through openings 16 in the extension 12, these openings being of sufficient size to permit the screws to operate therein. These screws are secured, as by pins 17, in the ends of the arms and the parts are held in locked position by means of lock nuts 18 threaded on the screws and bearing against the under side of the extension 12.

The thin metal sheet 9 is of sufficient flexibility so that when the lock nuts 18 are loosened the plates 8 and the sheet 9 will drop of themselves against the wire and breast roll, so that the lip or edge 10 of the plate will align itself with the roll widthwise of the machine, the arms 11 rocking on the extension 12. By a light touch on the handles 15 the operator may determine by the feel whether the lip 10 is in contact

with the roll, thus assuring himself that the parts are in aligned or parallel relation.

After this is done, the parts may be adjusted to provide a uniform gap between the lip 10 and the breast roll, this gap being just wide enough to prevent rubbing of the lip on the wire. While various expedients may be adopted for this, a convenient one is that shown in which there are provided micrometer screws 20 having operating handles 21, these screws being threaded through the frame 6, before referred to, and bearing at their inner ends against the lower parts of the arms. By adjusting these screws widthwise of the machine to the same extent, the arms 11 will be quickly rocked and a uniform gap provided across the machine. After this is done, the parts may be secured in locked position by the lock nuts 18.

It will thus be seen from the construction described that the lip or edge of the apron board may be readily adjusted so that the lip of the board is parallel to the wire and the desired gap between the edge and the wire is obtained.

While the invention has been shown and described in its preferred form, it will be understood that certain changes and variations may be made in the specific structure without departing from the invention, such structure being shown as illustrative of the invention.

What I claim is:

1. The combination in a Fourdrinier paper making machine, of the breast roll and the making wire, an apron board having a rigid portion and a loose portion, and means for locking the loose portion in adjusted position over the breast roll, the loose portion being of sufficient looseness that when the locking devices are released it will tend to align itself with the breast roll widthwise thereof.
2. The combination in a Fourdrinier paper making machine, of the breast roll and the making wire, an apron board having a rigid portion and a loose portion, means for locking the loose portion in adjusted position over the breast roll, the loose portion being of sufficient looseness that when the locking devices are released it will tend to align

itself with the breast roll widthwise thereof, and means for producing a gap between the edge of the loose portion and the roll of uniform height widthwise of the roll.

3. The combination in a Fourdrinier paper making machine, of the breast roll and the making wire, an apron board having a rigid portion, a portion loosely united therewith including a plurality of separate plates extending widthwise of the roll, rocking supports for the latter portion, and means for locking the loose portion in adjusted position over the breast roll.

4. The combination in a Fourdrinier paper making machine, of the breast roll and the making wire, an apron board having a rigid portion, a portion loosely united therewith, rocking supports for the latter, adjusting devices for rocking the supports, and means for locking the loose portion in adjusted position over the breast roll.

5. The combination in a Fourdrinier paper making machine, of the breast roll and the making wire, an apron board having a rigid portion, a loose metal sheet secured to the rigid portion, a plurality of plates extending lengthwise of the roll to which the sheet is secured, rocker supports for the plates, adjusting means for rocking the supports and means for locking the supports in adjusted position.

6. An apron board for Fourdrinier paper making machines comprising a rigid part, a thin metal sheet secured thereto, a plurality of plates extending widthwise of the roll to which the sheet is secured, and adjustable supports for the plates.

7. The combination in a Fourdrinier paper making machine, of the breast roll and the making wire, an apron board having a rigid portion, a portion loosely united therewith, rocking supports for the latter, adjusting screws bearing against the supports for rocking them, screws fixed to the supports, and locking nuts cooperating with the latter screws.

In testimony whereof, I have hereunto set my hand.

CHARLES W. VALENTINE.
